UNITED STATES PATENT OFFICE.

WALLACE F. GOODNOW, OF GREENWICH, CONNECTICUT, AND GEORGE H. VICKERS, OF EASTWOOD, NEW YORK, ASSIGNEES TO PIERCE, BUTLER & PIERCE MANUFACTURING CORP., OF SYRACUSE, NEW YORK, A CORPORATION OF NEW YORK.

HOT-WATER AND STEAM HEATER.

Application filed December 24, 1923. Serial No. 682,425.

This invention relates to steam and hot water heaters composed of upright hollow sections arranged face to face in sequence from front to rear and constructed so as to 5 form when assembled, a combustion chamber, a horizontal flue above the combustion chamber and fire passages leading from the combustion chamber to the flue together with suitable connections for allowing the heating fluid such as water or steam, to circulate through the several sections and entirely 10 around the combustion chamber, flue and fire passages.

In addition to the desirability of making 15 the heater symmetrical with reference to a longitudinal vertical center and incidentally, the use of separate fire passages connecting the combustion chamber and flue at opposite sides of the said center, the main object 20 is to provide separate sets of baffle plates, one set for each set of passages, movably and preferably rotatably mounted therein for regulating the effective capacity of the passages and also the direction of flow of the 25 products of combustion from the combustion chamber to the flue.

Another object is to utilize these baffle plates as a means for cleaning the walls of the passages from accumulations of soot or 30 other deposits resulting from combustion of the fuel.

Other objects and uses relating to specific 35 parts of the heater will be brought out in the following description.

In the drawings:

Figure 1 is a perspective view of a steam or hot water heater embodying the various features of this invention.

Figure 2 is an enlarged horizontal sectional view of the same taken in the plane of line 2-2, Figure 1.

Figures 3 and 4 are transverse vertical sectional views taken respectively in the planes of lines 3-3 and 4-4, Figure 2.

As illustrated, this heater comprises a 45 low upright front, intermediate and rear sections -1-, -2- and -3- of substantially the same size and form in outline arranged in sequence from front to rear and 50 constructed to form a combustion chamber -4-, an ash pit -5-, a horizontal flue -10- overlying the combustion chamber in spaced relation thereto and intervening passages -7- connecting the combustion cham-

ber -4- with the flue -10-, said sections 55 being also provided with water chambers surrounding the combustion chamber, ash pit and flue and communicating with each other for the circulation of the water and steam.

The front section -1- extends across the front end of the combustion chamber to form the front wall thereof, and is provided with a fuel opening -8-, a clean-out opening -9- and an additional clean-out opening -10'- registering respectively with the upper portion of the combustion chamber -4-, the ash pit -5- and the flue -10- and normally closed by suitable doors -8', -9' and -10', Figure 1.

The intermediate sections -2- are substantially identical and therefore, interchangeable and being symmetrical with reference to the longitudinal vertical center, may be reversed, said sections being provided with central registering openings forming parts of the combustion chamber -4- and ash pit -5- and with additional registering openings, forming parts of the flue -10-.

The walls of each section surrounding the combustion chamber and ash pit openings and also surrounding the flue openings are hollow or cored to form opposite water-containing legs -11-, a water-containing base -12-, a steam and water-containing dome -13- and a hollow partition -14-, the latter being interposed between the top of the combustion chamber -4- and flue -10-.

The rear section -3- extends across the rear side of the combustion chamber to form the rear wall thereof and is provided near its lower end with a draft opening -15- and a draft door -16- which may be 95 opened and closed by any suitable means such as an automatic regulator -17-, Figure 1, for regulating the draft.

The upper portion of the rear section is also provided with an outlet for connection 100 with a suitable smoke pipe -18- leading from the rear end of the flue -10-.

The front, intermediate and rear sections are clamped together face to face to form air and gas-tight joints between them by 105 means of tie bolts -19- which are passed through registering openings in uncored portions of the bottom and top of the sev-

eral sections at opposite sides of the vertical centers thereof.

Communication is established between the water chambers of the several sections by means of nipples —20— which are engaged in registering apertures in the lower and upper portions of the adjacent sides of said sections, the lower nipples serving to connect the several water bases —12— midway between the water legs —11— while the upper set of nipples serve to connect the several domes —13— midway between the sides of the sections.

Suitable grate bars —21— are supported at their front and rear ends in suitable bearings on the front section —1— and rear section —3— in a horizontal plane between the ash pit —5— and combustion chamber —4— as set forth in my pending application Serial Number 682,424, filed December 24, 1923, and not necessary to herein further illustrate or describe.

The adjacent faces of the portions of the sections above the flue —10— constituting the domes —13— are arranged in close proximity to each other to form what may be termed a crown sheet —21'— which extends from side to side of the several sections and forms the top wall of the flue —10— and fire passage —7—, while the adjacent sides of the sections below the crown sheet and extending downwardly to substantially the horizontal plane of the lower edge of the fuel opening —8—, except the central portion of the horizontal partition —14—, are chambered to form the separate fire passages —7— extending from opposite sides of the combustion chamber —4— to the crown sheet —21'—.

The central portions of the front and rear sides of the hollow partitions —14— are offset in opposite directions to bring their adjacent faces into close relation to form division walls for separating the opposite fire passages —7— one from the other between the combustion chamber —4— and flue —10— and thereby causing the products of combustion to spread out laterally to opposite sides of the partition —14— for distributing the heat more uniformly to various parts of the sections in transit to the flue —10—.

Suitable means is provided for regulating the effective capacity of the fire passages —7— and also for regulating the direction of flow of the products of combustion from the combustion chamber to the flue and for this purpose is provided a pair of rock shafts —22— and —22'— extending through registering uncored openings in the front and intermediate sections and journaled at their rear ends in suitable bearings in the front wall of the rear section —3— as shown in Figure 2, said rods being arranged in parallel relation so as to extend

through the intermediate portions of the fire passages —7— at opposite sides of the partition —14—, the front ends of the rods being exposed in the front of the heater for receiving a suitable hand crank such as the shaker handle for the grates whereby they may be turned, each independently of the other.

Each of these rock shafts carries a plural-ity of baffle plates —23— and —23'—, one for each of the fire passages —7—, the plates of each rock shaft being adapted to turn therewith for regulating the effective capacity of the fire passages and also for regulating the direction of flow of the products of combustion from the combustion chamber to the flue.

As illustrated, the rock shafts —22— and —22'— are angular in cross section while the holes in the baffle plates for receiving them are also of angular cross section to cause the corresponding set of baffle plates to turn with its shaft and at the same time, permitting the shafts to be easily and quickly withdrawn from or reinserted into their respective sets of plates.

Some of the plates as —23—, in the major portions of the fire passages —7— preferably from the rear section —3— forwardly through several of the intermediate sections, extend radially equal distances in opposite directions from their respective rock shafts —22— and —22'—, while other baffle plates —23'— in the remaining fire passages —7— nearer the front of the heater extend inwardly and radially from one side only of their respective shafts thereby leaving the outer portions of the fire passages open for the direct upward passage of the products of combustion around the outside of the baffle plates —23'— from the combustion chamber to corresponding sides of the flue —10—.

In other words, the baffle plates —23— are of substantially the same area as the cross sectional area of their respective fire passages —7—, while the area of the remaining baffle plates —23'— is substantially equal to half the cross sectional area of the corresponding fire passages —7—, and it therefore, follows that when the baffle plates are in their maximum closed positions, the products of combustion rising from the rear of the combustion chamber will be caused to travel forwardly through a considerable portion of the area of the combustion chamber and thence upwardly around the outer ends of the baffle plates —23'— to opposite sides of the overlying portions of the flue —10— and thence rearwardly through the said flue to the smoke pipe —18—.

It is evident, however, that the turning of either of the rock shafts and their corresponding baffle plates from their normal closed positions, will vary the effective capacity of the corresponding fire passages

and may also affect the direction of the flow of the products of combustion from the combustion chamber to the flue —10—.

For example, by turning either set of baffles a quarter-turn will permit the major portion of the products of combustion to pass from the combustion chamber through the corresponding passages —7— and directly to the adjacent side of the flue providing the opposite set of baffle plates remain in their horizontal positions as shown in Figs. 3 and 4.

Another object in mounting these baffle plates upon their respective rock shafts and within the corresponding fire passages is to utilize their rotary movement in cleaning the walls of said passages from soot and other deposits resulting from combustion of the fuel thereby greatly expediting the interchange of heat from the products of combustion to the water in the several sections and materially increasing the efficiency of the heater.

The operation of our invention will now be readily understood upon reference to the foregoing description and the accompanying drawing and it is evident that various changes may be made in the detail construc-

tion and arrangement of the various parts of the heater without departing from the spirit 30 of this invention.

We claim:

1. A water heater comprising an upright shell having a combustion chamber and a smoke flue above the combustion chamber and both extending from the front wall to the rear wall of the shell, said shell having separate upright fire passages connecting opposite sides of the combustion chamber with corresponding sides of the smoke flue, partitions extending vertically between the top of the combustion chamber and bottom of the smoke flue and between opposite upright fire passages, and baffle plates rotatably mounted in said fire passages at opposite sides of the partition for regulating the passage of the products of combustion from the combustion chamber to the smoke flue. 35

2. A water heater as in claim 1 in which the baffle plates at each side of the partition are connected for simultaneous operation. 40 45

In witness whereof we have hereunto set our hands this 11th day of December, 1923.

WALLACE F. GOODNOW.
GEORGE H. VICKERS.
